POCKET STAPLING MACHINE

Charles M. Palmer, Washington, D. C., assignor
to Speed Products Company, Inc., New York,
N. Y., a corporation of New York

Application April 29, 1948, Serial No 24,011

19 Claims. (Cl. 1—49)

1 The subject matter of this invention is an advantageously effective and simplified but serviceable stapling machine featuring as one object the utilization of a novel staple driver in the form of a one piece swiveled bar preferably although not necessarily substantially coextensive with the length of the staple carrying magazine and adapted when desired to be bodily but quickly detached therefrom to permit full and prompt access to the inside faces of the magazine and to the staple guideway thereof upon withdrawal of the staple follower out of the magazine. More specifically one principal feature of the improved stapling machine according to my invention is predicated upon guide means at the rear part of the magazine constituting guide channels with spaced flanges inwardly overhanging the sides of the magazine for linearly directing channeled shaped bearing means upon which a one piece staple driver is appropriately swiveled to permit rotation of the latter in a direction towards or away from the staple guideway at the front part of the magazine. Another principal feature is concerned with effectively but removably anchoring the channel shaped bearing on the magazine by disengagable and complementary detent means associated with the magazine, with the bearing, and with the guide means. The primary purpose of the invention is to mount the driver on a relatively thin but strong channel shaped bearing adapted to be quickly thrust into an interlocking but secured relation with the magazine to thereafter permit the one piece driver to be swiveled or rotated relative to both the bearing and magazine to be in full superimposed relation with the magazine for positioning of a depending blade portion of the driver in alignment with the staple guideway at the front part of the magazine whereby upon displacement of the forward part of the driver downwardly relative to the bearing and towards the magazine the blade portion thereof enters the guideway and drives the staple therein out of the magazine and onto a clinching anvil. Another purpose of the invention is to permit when desired prompt unlocking of the bearing from both the magazine and guide means to provide for complete disassociation of the driving means from the magazine. Another object is concerned with the provision of a novel stapling machine wherein the staple driving means is carried by a bearing sustaining the staple follower. A further object is realized in the provision of a one piece bar constituting the driving means for expelling a staple from the magazine and serving as a handle to facilitate

2 attaching or detaching the bearing to and from the magazine. Another important object comprehends the utilization of supplementary locking means to preclude accidental disassociation of companion but separate detent means for removably locking the bearing or carriage to the magazine. Other important features and functional and structural advantages of the invention will appear from the following detailed specification taken with the accompanying drawings wherein:

Fig. 1 is a perspective view of the stapling machine according to one embodiment of my invention illustrating the bearing which rotatably carries the one piece driver detached from the magazine.

Fig. 1^a is a transverse sectional view on the line 1^a—1^a of Fig. 1 illustrating the guide openings for receiving the bearing.

Fig. 1^b is a transverse sectional view on the line 1^b—1^b illustrating the offset shoulders or margins of the bearing.

Fig. 2 is a longitudinal and vertical sectional view of Fig. 1 however showing the bearing locked on the magazine and the one piece driver in full superimposed and operative relation therewith with the depending reciprocable blade thereof in alignment with the staple guideway and awaiting to drive a staple therefrom.

Fig. 3 is a side elevational view of Fig. 1 but with the driver locked on the magazine but swiveled or rotated to overhang the latter.

Fig. 3A is a view taken on the line 3A—3A of Fig. 3.

Fig. 4 is a transverse sectional view on the line 4—4 of Fig. 2.

Fig. 5 is a fragmentary and enlarged perspective view of the magazine.

Fig. 6 is an inverted perspective view of the magazine to illustrate the swiveled anvil.

Fig. 7 is an enlarged perspective view of the channeled bearing.

Fig. 8 is an enlarged sectional view taken approximately on the line 8—8 of Fig. 4.

Fig. 9 is a view similar to Fig. 8 however illustrating the cooperating detents of the primary and secondary locking means in alignment.

Fig. 9A is a perspective view of a slightly modified bearing.

Fig. 9B is a fragmentary view of Fig. 2 but with the bearing of Fig. 9B removably locked to the rear end of the magazine.

Fig. 9C is an end view of Fig. 9B.

Fig. 10 is a perspective view of the pocket stapling machine according to the form shown in

Fig. 2 but without an anvil and illustrating the driver slotted to provide for both linear and rotational displacement thereof relative to the bearing.

Fig. 11 is a view similar to Fig. 10 showing in dash and dot lines the driver slidably pulled rearwardly to clear the stops and in full lines swung laterally of the magazine.

Fig. 12 is a sectional view on the line 12—12 of Fig. 10.

Fig. 13 is a side elevational view of a stapling machine according to the invention wherein the guide rod for the follower is permanently carried by the bearing and wherein the rotatable and reciprocable driver is swiveled rearwardly to overhang the magazine.

Fig. 14 is a longitudinal sectional view of Fig. 13 showing the staple driver in an operative position to eject staples from the magazine and also exhibiting certain parts on a larger scale to advantageously illustrate the primary and secondary locking means.

Fig. 14A is an end view of Fig. 14.

Fig. 15 is a perspective view of the magazine shown in Fig. 13 however completely empty.

Fig. 16 is a perspective view showing the driver of Fig. 13 swiveled to the rear of the bearing which non-rotatably and fixedly carries the guide rod for the slidably pusher or follower.

Fig. 16A is an end view of the follower or pusher taken on the line 16A—16A of Fig. 16, and

Fig. 17 is a perspective view of a slightly modified detachable bearing.

Illustrative of the embodiments disclosed, the stapling machine SM comprises magazine M for housing a strip of inverted U-shaped staples S, the bearing or support B, the one piece driver or bar D, the staple pusher or follower F, and the sheath or guide G.

The magazine is a one piece shell of suitable sheet metal having bottom wall 10 for directly supporting the spaced legs of the staple strip, the upstanding side walls 11 for guiding the staples towards guideway 12, and inwardly overhanging flanges 13 which it is important to observe have the dual purpose of preventing admission of staples into the magazine through the open top thereof and also serve to prevent displacement of the staple strip after having been admitted into the magazine through the open rear end 14 (Figs. 1 and 6) of the magazine.

The foremost staple of the strip is projected into the staple guideway 12 by spaced forwardly extending legs 15 of the staple pusher or follower F having depending perforated ears 16 slidably guided on rod 17 fixedly carrying at its rear end block 18 against which the rear end of the normally expanded coiled spring 19 bears. This spring surrounds rod 17 and also abuts the rear ear 16 to urge the follower constantly in a direction towards raceway 12 constituted by the upwardly extending tongue 20 and the U-shaped sheath 21 having its front wall 22 appropriately spaced from tongue 20 and having its sides 23 fixedly anchored to the side walls 11 of the magazine.

Of importance are the transversely spaced but aligned and upwardly extending projections or detents 24 struck out of the inwardly overhanging flanges 13 of the magazine.

Slightly offset but to the rear of the lower aligned detents 24 are the upper aligned and depending projections or detents 25 struck out of the spaced flanges 26 of the guide G. Flanges 26 are above and spaced from flanges 13 of the mag-

azine to define therewith spaced rectilinear gaps 27 (Fig. 1a). Flanges 26 are bent inwardly from sides 28 of the guide G and these sides straddle and are against the upstanding sides 11 of the magazine having its bottom wall 10 secured to the bottom wall 29 of guide G by the spaced rivets 30.

Effectively interlocking with aligned detents 24 of the magazine are the walls of the transversely aligned indentations 31 formed by upwardly projecting detents or projections 32 struck out of the rectilinear bearing or plate B provided with the central boss or seat 33 extending above the elevation of the margins or shoulders 34 which embody projections 32, the arrangement being such that shoulders 34 may be quickly set between the vertically spaced flanges 13 and 26 into the aligned guide gaps 27 whereby the bearing B may be bodily slid towards the front of the magazine. On such displacement spaced detents 32 of the sheet metal bearing B snap slightly by the downwardly projecting detents 25 of guide G to also interlock with or snap into the upwardly projecting detents 24 on the magazine (Fig. 8). By this arrangement primary and supplementary locking means are provided, the primary locking means being constituted by the complementary and separable detents 24 and 32 while the supplementary locking means may be said to be characterized by the cooperating detents 25 and 32, detents 25 also frictionally bearing against projections 32 and serving to prevent accidental disengagement of the primary locking means.

As illustrated in Fig. 8 detent 25 is out of alignment with detents 24 and 32. These detents of course may be in alignment as illustrated in Fig. 9. In either case the intervening detents are held disengageably interlocked with the detents of the magazine. In the form shown in Fig. 9 detent 25" frictionally bears against detent 32" and serves as supplementary means to maintain the lower cooperating detents 32" and 24" against accidental separation.

The staple driver D may be said to be a handle to facilitate shifting of the bearing B into and from its interlocked relation with the magazine M and guide G. Driver D is formed from the relatively hard and resilient one piece steel bar having the horizontal rear or posterior portion 35, the intermediate inclined portion 36, the depressed portion 37 and the forwardly arranged and depending T shaped driving blade 38 adapted to be elevated above guards or stops 39 and into sheath 21 to be arranged over the forward staple of the staple strip S (Fig. 2).

More particularly the rear rectilinear end 35 of the driver rests on the rectilinear boss 33 of the bearing B and is at all times spaced from shoulders 34 of the latter. Fulcrum pin 40 appropriately upset, at its ends rotatably retains end 35 against boss 33 and driver D is consequently swiveled relative to the bearing B or the latter may be swiveled in respect to the driver.

When the bearing B is interlocked with the magazine, it is effectively anchored against accidental displacement and consequently the driver may be swiveled from its overhanging position shown in Fig. 3 about pin 40 to its staple driving position illustrated in Fig. 2 where the slidably guided driving blade 38 if directed downwardly upon application of manual pressure on the depressed portion 37 drives or expels the staple from the guideway onto the clinching anvil A.

In the position of the driver shown in Fig. 3, it may serve as a handle adapted to be grasped and pulled outwardly. This action causes the inter-

mediate detents 32 to snap over and be free of the cooperating interlocking detents 25 and 24 and almost coincident with such disengagement the bearing B is completely withdrawn from the magazine. It follows that the T-shaped block 18 fixedly carrying rod 17 may then be lifted from aligned notches 41, thus unlocking from the magazine and therefore the follower rod may be withdrawn through the rear open end 14 of the magazine carrying with it the staple follower F.

With the follower or pusher F out of the magazine and the latter empty of staples full access may be had to the interior of the magazine to clean the latter of accumulated wads of glue at which time even the guideway 12 may now be cleared of clogged or jammed staples or pieces thereof. Of course once the pusher F is removed and the interior of the magazine is clear of interference due to pieces of glue or fragments of staples, a new strip of staples may be quickly inserted into the magazine however through the rear opening 14 only after which rod 17 with the sliding pusher F and spring 19 thereon is restored therein and block 18 locked by the walls of notches 41 whereby each succeeding foremost staple of the strip is always urged in the raceway and under the driving blade 38.

Having locked block 18 to the magazine filled with a supply of staples, the accessible front end 60 of the bearing B is now inserted in the guide openings 27 (Fig. 1A) and urged forwardly by pushing the driver D forwardly. This action causes the bearing to interlock with both the magazine and guide as previously pointed out. Therefore driver D may be swung to arrange its driving blade 38 towards the near sheath 21 at which time due to looseness or play of the rear end 35 on fulcrum pin 40, the blade 38 may be conveniently lifted over guards or stops 39 into the guideway 12 where it is reciprocably guided to expel the foremost staple after which upon release of the manual downward pressure on the driver, the intermedial portion 36, the depressed portion 37, and the driving blade automatically retract due to the inherent resiliency of the driver to arrange the blade just above the foremost staple although it should be noted that downward displacement of the blade is limited when shoulders 42 of the driving blade strike stops or guards 39.

Blade 38 in Fig. 2 may be lifted out of the guideway 12 to clear stops 39 after which the intermediate portion 36 is actuated to swing this driver rearwardly. Thereafter upon the application of an outwardly directed thrust on the driver the bearing becomes unlocked and free of the magazine.

If desired an elongated clearing guide slot 45 (Fig. 10) may be provided in the driver to permit the latter limited linear as well as rotational displacement whereby the driving blade need not be lifted over the stops 39. In this connection, the driver is bodily and linearly displaced towards pin 40 (note dash and dot lines in Fig. 11) whereby blade 38 is free of stops 39 after which it may be swung laterally to clear the magazine preparatory to detaching the bearing therefrom. Conversely the driver may be set over the magazine in the position shown by the dot and dash lines in Fig. 11 and thereafter on linearly shifting thereof towards sheath 21 blade 38 moves between the stops 39 and into the guideway or raceway above the foremost staple at which time the rear end of slot 14 strikes the upset fulcrum pin 40.

Appropriately swiveled to the bottom wall 10 of

the magazine is the clinching anvil A provided with detent 46 adapted to removably snap into the opening or socket 47 in wall 10. Thus with the anvil swung to one side of the magazine, the stapling machine may be employed as a tacker.

In the form according to Figs. 13-16 the bearing B' is provided with depending ears 50' and 51' having aligned square shaped openings 52' (Fig. 17) through which a correspondingly shaped rod 53' is threaded. The rear end of rod 53' is upset to fixedly anchor the bearing B' thereto. Pusher F' is slidably and non-rotatably guided on rod 53' in that depending lug 46' thereof embody correspondingly shaped non-circular openings 54'. The normally expanded spring 19' surrounds the square shaped rod 53' and abuts both the bearing B' and pusher F' for always urging the latter forwardly. The rear depending ear 51' partly closes the rear end of the magazine. In other aspects the form according to Figs. 13 to 16 is along the lines of the form shown in Figs. 1-8 and parts in Figs. 13 to 16 corresponding to similar parts in Figs. 1 to 8 have been primed. In Fig. 17 the bearing is along the bearing shown in Fig. 14 and portions in Fig. 17 corresponding to similar parts in Fig. 14A have been raised to the exponent "a." With the bearing shown in Fig. 17 applied to the magazine, end 51' would fully close the end of the magazine in the manner illustrated in Fig. 9C wherein the end closure or lug 80 (Fig. 9A) removably fits within guard G to close the magazine. In other aspects the form shown in Fig. 17 is along the lines exhibited in Figs. 14 and 16 and the bearing in Figs. 9A, 9B and 9C is along the lines shown in Figs. 1-7.

In Fig. 14 the driver D' is above the foremost staple in the raceway 12' and is adapted to be depressed to eject the staple onto the anvil. By lifting the blade 38' above stops 39'; the driver thereafter can be rotated or swiveled relative to bearing B' to the position shown in Fig. 13. Subsequently an outward thrust will unlock and disengage bearing B' from both the magazine M' and guide G' and since the square rod 53' is fixed to bearing B' the latter, spring 19' and pusher or follower F' will also be bodily withdrawn from the magazine which may now be quickly supplied with a new staple strip after which the pusher is again inserted into the magazine to be in back of the staples at which time lips 34' of the bearing are interposed between flanges 13' and flanges 26' and pursuant thereto a forwardly directed thrust is applied to the driver. By such action detents 34' of the bearing snap automatically into engagement with the companion detents 24' and 25', thereby holding bearing B' against accidental displacement. Driver D' may now be rotated relative to the bearing for arranging the blade 38' in line with the staple raceway or guideway 12'.

In all the forms disclosed the driver can be withdrawn completely from above the vertical staple guideway and thereafter rotated and utilized as a handle for detaching and removing the bearing from the magazine and in the embodiment according to Figs. 13 to 16 such action also completely withdraws the staple pusher, its guide rod, as well as the helicoidal spring surrounding the latter.

Preferably when the driver is swung rearwardly of the bearing, the forward portion as 60 in Figs. 1 and 3 and 60' in Fig. 16 thereof becomes uncovered or fully exposed to facilitate its threading between guide G and the magazine M and for strengthening purposes the blade of the driver

75

(note for example Fig. 10) is provided with a boss or rib 70 slidably and removably receivable and guided in the channel 71 communicating with the staple raceway formed by the fixed sheath 21 and the upstanding tongue 20.

In the form illustrated in Figs. 2 and 3, the rear end of the bearing B extends above the aligned openings 41, and prevents withdrawal of the end plate or block 18 when the bearing is in a locked relation. In accordance with the embodiment shown in Figs. 13, 14 and 14A and as previously stated the rear end 51' serves in part as closure means for the rear end of the staple admitting opening 14'.

However in all of the embodiments according to the invention herein the driver is a one piece metal bar adequately resilient and effectively swiveled on the bearing and adapted to be flexed downwardly relative thereto when locked preparatory to driving a staple out of the magazine and pursuant to such action and upon removal of finger pressure on the driver the latter automatically is elevated or retracted due to its own resiliency to arrange the driving blade again just above the foremost staple. In all the forms disclosed the driver is carried by the detachable bearing and in Figs. 13-15 may be said to permanently carry the staple follower and in each instant however the driver in fact may be considered as a swiveled handle to facilitate threading and locking the bearing or carriage B to the magazine. Of course when the driver is swung laterally or rearwardly of the magazine it also serves to facilitate detaching the bearing from the magazine.

By the present invention it is apparent that the herein stapling machine comprises relatively few parts each simple in structure and when such parts are assembled they constitute a relatively small yet simplified stapling machine conveniently adapted to be carried about by the user and in a small pocket of the latter's clothing.

Various changes may be made in details of construction and arrangement of parts without departing from the spirit of the invention or sacrificing any of the advantages thereof inherent therein.

I claim:

1. In a stapling machine, a magazine for housing a strip of staples and having a raceway, bearing means, means disconnectably holding said bearing means on said magazine, driving means having a portion sustained by said bearing means and having a driving blade slidably and removably guided relative to said raceway for ejecting the foremost staple of said strip out of said raceway, and means rotatably holding said portion on said bearing means.

2. In a stapling machine, a magazine for housing a strip of staples and having a raceway, a bearing, means on said magazine and bearing for disconnectably holding said bearing means on said magazine, driving means having a portion sustained by said bearing and having a driving blade slidably and removably guided relative to said raceway for ejecting the foremost staple of said strip out of said raceway, and means rotatably holding said portion on said bearing.

3. In a stapling machine, a magazine for housing a strip of staples and having a raceway, a bearing, complementary locking means disconnectably holding said bearing means on said magazine, driving means having a portion sustained by said bearing and having a driving blade slidably and removably guided relative to said race-

way for ejecting the foremost staple of said strip out of said raceway, and means rotatably holding said portion on said bearing.

4. In a stapling machine, a magazine for housing a strip of staples and having a raceway, a bearing, cooperative detent means disconnectably holding said bearing means on said magazine, driving means having a portion sustained by said bearing and having a driving blade slidably and removably guided relative to said raceway for ejecting the foremost staple of said strip out of said raceway, and means movably holding said portion on said bearing for shifting said driving means laterally of said magazine.

5. In a stapling machine, a magazine for housing a strip of staples and having a raceway, a bearing, primary locking means disconnectably holding said bearing means on said magazine, driving means having a portion sustained by said bearing and having a driving blade slidably and removably guided relative to said raceway for ejecting the foremost staple of said strip out of said raceway, means movably holding said portion on said bearing for shifting said driving means laterally of and to the rear of said magazine, and supplementary locking means to preclude accidental separation of said primary locking means.

6. In a stapling machine, a magazine for housing a strip of staples and having a raceway and including spaced detents, a bearing having means removably interlocking with said detents, driving means having a portion mounted on said bearing and having a driving blade slidably and removably guided relative to said raceway for ejecting the foremost staple of said strip out of said raceway, and means rotatably holding said portion on said bearing.

7. In a stapling machine, a magazine for housing a strip of staples and having a raceway and embodying aligned flanges including spaced detents, a bearing having spaced detents removably interlocking with said first mentioned detents, driving means having a portion mounted on said bearing and having a driving blade slidably and removably guided relative to said raceway for ejecting the foremost staple of said strip out of said raceway, and means rotatably holding said portion on said bearing.

8. In combination, a magazine for housing a strip of staples and having a vertical raceway for receiving the foremost staple of said strip, a plate mounted on said magazine, driving means in part superimposed on said plate and having a portion slidably and removably guided relative to said raceway, means detachably holding said plate on said magazine, and means rotatably sustaining said driving means on said plate.

9. In a stapling machine, a magazine for housing a strip of staples and having a raceway and embodying aligned flanges including spaced upwardly projecting detents, guide means secured to said magazine and having depending detents, a bearing slidably interposed between said projecting and depending detents and detachably interlocking therewith, driving means comprising a one piece resilient bar having a relatively flat rear portion seated on said bearing and having a depending driving blade at the front end thereof slidably and removably guided relative to said raceway for ejecting the foremost staple of said strip therefrom, and means to swivel said rear portion on said bearing.

10. In a stapling machine, a magazine for housing a strip of staples and having a raceway and

embodying aligned flanges including spaced upwardly projecting detents, guide means secured to said magazine and having depending detents spaced from and slightly to the rear of said projecting detents, a bearing slidably interposed between said projecting and depending detents and having means detachably interlocking therewith, driving means comprising a one piece slightly resilient bar having a relatively flat rear portion seated on said bearing and having a depending driving blade at the front end thereof slidably and removably guided relative to said raceway for ejecting the foremost staple of said strip therefrom, and means rotatably holding said rear portion on said bearing.

11. In combination, a magazine for housing a strip of staples and having a vertical raceway for receiving the foremost staple of said strip, a plate having a boss and laterally extending shoulders disposed below said boss, driving means having a rear part seated on said boss and spaced from said shoulders and having a front depending portion slidably and removably guided relative to said raceway, means detachably holding said shoulders on said magazine, and means rotatably sustaining said rear part on said boss.

12. In combination, a magazine for housing a strip of staples and having a vertical raceway for receiving the foremost staple of said strip and including inwardly overhanging flanges, a plate having a boss and laterally extending shoulders below said boss, driving means having a rear part seated on said plate and spaced from said shoulders and having a front depending portion slidably and removably guided relative to said raceway, means rotatably sustaining said rear part of said boss, guide means straddling said magazine and having inwardly overhanging flanges, and detachable and cooperative locking means projecting from said shoulders and said flanges.

13. In combination, a magazine for housing a strip of staples and having a vertical raceway for receiving the foremost staple of said strip and including spaced stops, a plate having a boss and laterally extending shoulders below said boss, driving means comprising a one piece slightly resilient bar having a rear part seated on said boss and spaced from said shoulders and having a front depending portion slidably and removably guided relative to said raceway and including means cooperating with said stops to limit insertion therein into said raceway, means detachably holding said shoulders on said magazine, means rotatably sustaining said rear part on said boss, said bar having an intermediate part disposed above and along said magazine, said front depending portion adapted to be lifted out of said raceway and clear of said magazine whereby said driving means may be swung to the rear of said magazine to constitute a handle to facilitate disengagement of said shoulders from said magazine and the withdrawal of said plate therefrom.

14. In a stapling machine, a magazine for housing a strip of staples and having a raceway and embodying aligned flanges including spaced upwardly projecting detents and including spaced stops, guide means secured to said magazine and having depending detents, a bearing slidably interposed between said projecting and depending detents and having means detachably interlocking therewith, driving means having a relatively flat rear portion provided with a slot and seated on said bearing and having a depending driving blade at the front end thereof slidably and removably guided relative to said raceway for eject-

ing the foremost staple of said strip therefrom, and pin means retained against said rear portion and bearing and extending through said slot and cooperating with the walls thereof to provide a slideable and swingable connection to permit linear displacement of said driving means towards or away from said stops and to permit rotational displacement of said driving means relative to said bearing.

15. In combination, a magazine for housing a strip of staples and having a vertical raceway for receiving the foremost staple of said strip, a plate, means detachably locking said plate at the rear part of said magazine, spring controlled staple follower means removably disposed within said magazine and permanently sustained by said plate, driving means comprising a one piece resilient bar substantially coextensive with the length of said magazine and having a rear flat part seated on said plate and embodying a front depending staple driving portion slidably and removably guided relative to said raceway, and means rotatably sustaining said rear part on said plate.

16. In combination, a magazine for housing a strip of staples and having a vertical raceway for receiving the foremost staple of said strip, a plate having depending means, a rod carried by said depending means, means detachably locking said plate at the rear part of said magazine, spring controlled and slideable staple follower means removably disposed within said magazine and non-rotatably sustained by said rod, driving means comprising a one piece resilient bar substantially coextensive with the length of said magazine and having a rear flat part seated on said plate and embodying a front depending driving portion slidably and removably guided relative to said raceway, and means rotatably sustaining said rear part on said plate, said driving means adapted to be rotated relative to said plate to overhang said magazine and adapted to receive a rearwardly directed thrust for disabling said means detachably locking said plate and concomitantly withdraw said staple follower means from said magazine.

17. In combination, a magazine for housing a strip of staples and having a vertical raceway for receiving the foremost staple of said strip, a plate, means detachably locking said plate at the rear part of said magazine, driving means comprising a one piece resilient bar substantially coextensive with the length of said magazine and having a rear part seated on said plate and embodying a front depending driving portion slidably and removably guided relative to said raceway, means rotatably sustaining said rear part on said plate, said plate having depending means to obstruct the rear part of said magazine.

18. In a stapling machine, a magazine for housing a strip of staples and having a raceway and embodying aligned flanges including spaced upwardly projecting detents, guide means secured to said magazine and having depending detents in alignment with said projecting detents, a bearing slidably interposed between said projecting and depending detents and having detent means detachably engaging therewith, resilient driving means having a relatively flat rear portion seated on said bearing and having a depending staple driving blade at the front end thereof slidably and removably guided relative to said raceway for ejecting the foremost staple of said strip therefrom, and means to swivel said rear portion on said bearing.

11

19. In a stapling machine, a magazine for housing a strip of staples and having a raceway and embodying aligned flanges including spaced upwardly projecting detents, guide means secured to said magazine and having depending detents, a bearing slidably interposed between said projecting and depending detents and including detent means detachably interlocking with said aforementioned detents, driving means having a

5

12

relatively flat rear portion seated on said bearing and having a depending driving blade at the front end thereof slidably and removably guided relative to said raceway for ejecting the foremost staple of said strip therefrom, and means to swivel said rear portion on said bearing.

CHARLES M. PALMER.
